G. L. SCHEEL.
HAIR DRYING DEVICE.
APPLICATION FILED NOV. 3, 1915.

1,190,017.

Patented July 4, 1916.

UNITED STATES PATENT OFFICE.

GEORGE L. SCHEEL, OF CHICAGO, ILLINOIS.

HAIR-DRYING DEVICE.

1,190,017.

Specification of Letters Patent.

Patented July 4, 1916.

Application filed November 3, 1915. Serial No. 59,419.

To all whom it may concern:

Be it known that I, GEORGE L. SCHEEL, a citizen of the United States, and a resident of the city of Chicago, county of Cook and 5 State of Illinois, have invented certain new and useful Improvements in Hair-Drying Devices, of which the following is a specification.

My invention relates to improvements in 10 hair drying devices, and has for its object the production of a device of this character which will be of durable and economical construction, one which may be readily and easily operated, and one which will be 15 highly efficient in use.

Other objects will appear hereinafter.

The invention consists in the combinations and arrangements of parts hereinafter described and claimed.

20 The invention will be best understood by reference to the accompanying drawing forming a part of this specification, and in which,

Figure 1 is a longitudinal section through 25 a hair drying device embodying the invention, and Fig. 2 is an enlarged section taken on line $x-x$ of Fig. 1.

The preferred form of construction, as 30 illustrated in the drawing, comprises a comb consisting of a back 1 from one side of which project spaced teeth 2. Formed in the back 1 is a longitudinally extending cylindrical chamber 3 and a longitudinally extending air passage 4 from which lead 35 branch passages 5 opening in the direction of the teeth 2, as shown.

The chamber 3 opens in the outer end of 40 the comb and removably arranged therein is a heating element 6 in the form of a cylindrical metallic bar having a non-heat conducting handle or knob 7 at one end adapted, when said heating element is positioned in said chamber, to project from the comb so as to be readily engageable by 45 the fingers. The handle 7 is formed with a reduced shoulder 8 adapted to frictionally engage with the outer end portion of chamber 3 in order to yieldingly hold the heating element in position therein. Said chamber 50 is lined with a lining 9 of non-heat conducting material or semi-non-heat conducting material so as to prevent overheating of the back 1 in the use of the device, it being clear that were the back 1 permitted 55 to become very hot, there would be a possibility of scorching or burning the scalp or

any other part of the body against which the same might be placed.

At the opposite end of the comb is provided a depressible rubber bulb 10 through 60 the medium of which air may be forced through the passages 4 and 5. The bulb 10 is mounted at the under side of a handle 11 of non-heat conducting material which is securely fastened in the adjacent end of 65 back 1. Said handle 11 is formed with a passage 12 in which is arranged a tube 13 adapted to enter one end of bulb 10, the opposite end of said bulb being mounted in a cap 14 which is secured to the corresponding 70 end of said handle 11. The bulb 10 is thus removably held in position by engagement of the opposite ends thereof with tube 13 and cap 14, permitting of ready removal 75 of the same in case the same becomes worn or disabled so as to allow for ready renewal of the same. Flap valves 15 and 16 coöperate with the bulb 10 so that upon successive depression of the same air will be pumped thereby through the passages 4 and 80 5, as will be readily understood.

In use, the heating element 6 is heated over a gas jet or the like and when sufficiently heated is inserted into the chamber 3. The heat of said element is conducted 85 through the walls of the comb back and also through the open rearward end of said chamber which communicates with the corresponding end of passage 4 so that in the passage of air from the bulb 10 through 90 passages 4 and 5, the same will become heated as is of course desirable in connection with the function of the device, which is that of drying hair. The passage 4 tapers toward its outer end in order to effect 95 the uniform distribution of the air to the branch passages 5, and the latter are tapered toward their outer ends in order to concentrate the air immediately before discharged, and thus increase the pressure of 100 the stream of air discharged.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I

claim as new and desire to secure by Letters Patent is:

1. In a device of the class described, the combination of a comb comprising a back; teeth projecting from said back, there being a longitudinally extending air passage formed in said back having branch passages opening in the direction of said teeth; a heating element removably mounted in said back; and means for forcing air through said passages, substantially as described.
2. In a device of the class described, the combination of a comb comprising a back; teeth projecting from said back, there being a longitudinally extending air passage formed in said back having branch passages opening in the direction of said teeth; a longitudinally extending chamber also formed in said back opening in the outer end of the comb; a heating element removably mounted in said chamber; a non-heat conducting lining for said chamber;

and means for forcing air through said passages, substantially as described.

3. In a device of the class described, the combination of a comb comprising a back; teeth projecting from said back, there being a longitudinally extending air passage formed in said back having branch passages opening in the direction of said teeth; a longitudinally extending chamber also formed in said back opening in the outer end of the comb; a heating element removably mounted in said chamber; and means for forcing air through said passage or through said chamber when said heating element is removed, substantially as described.

In testimony whereof I have signed my name to this specification in the presence of two subscribing witnesses.

GEORGE L. SCHEEL.

Witnesses:

JOSHUA R. H. POTTS,
CORA F. SCHIEBER.
